(57) CLAIM

The ornamental design for a paint brush cover, as shown and described.

DESCRIPTION

FIG. 1 is a perspective view of a paint brush cover according to the design of the present invention;

FIG. 2 is a front view of the cover;

FIG. 3 is a back view of the cover;

FIG. 4 is a left side view of the cover;

FIG. 5 is a right side view of the cover;

FIG. 6 is a top view of the cover;

FIG. 7 is a bottom view of the cover; and,

FIG. 8 is a reference drawing of the cover in use.

The broken line showing of the brush is included for the purpose of illustrating environmental subject matter and forms no part of the claim.
